UNITED STATES PATENT OFFICE.

GEORGE AINSWORTH, OF GREAT NECK, NEW YORK.

SCREWLESS GLOBE HOLDER.

Application filed March 3, 1927. Serial No. 172,234.

My invention relates to that class of devices designed to support the one-piece globes of translucent glass, which are required in order to properly diffuse the light 5 from the high-powered type-C electric bulbs, commonly called nitrogen lamps.

Devices of this character, with which I am familiar, have a globe-enclosing portion which has an opening at its upper end, and 10 a socket is mounted inside of this upwardly extended portion and is screwed on to the usual loop employed in fixtures of this type; but as a canopy has to be placed over the entire device, this makes it quite difficult to 15 assemble.

My invention has for its object, to provide a globe support which will not only support the globe, but will at the same time hold the socket securely in position, and will also 20 permit the use of the most inexpensive form of electric light socket, thereby materially decreasing the cost of installation.

My means of accomplishing the foregoing object may be more readily understood 25 by having reference to the accompanying drawing, in which—

Fig. 1 is a side view, partly in section, of my improvement;

Fig. 2 is a cross-section, taken on the line 30 2—2 in Fig. 1, in the direction indicated by the arrows;

Fig. 3 is an end elevation of the device as shown in Fig. 1;

Figs. 4 and 5 show a modified form of 35 construction;

Fig. 6 is a detail view of the securing ring.

Similar reference numerals refer to similar parts throughout the entire description.

As shown in the drawings, the globe 1 40 (of which only a fragmentary portion is shown, as obviously it forms no part of my invention,) is shown resting upon the arms of a U-shaped yoke 2. The arms, 3 and 4, of the yoke 2 are angular, as clearly seen 45 in Fig. 2, and are fitted to coincide with the angular sides of a porcelain socket 5, which is mounted intermediate the two arms 3 and 4 of the yoke 2. It is apparent that these angular arms 3 and 4 prevent the rotation 50 of the socket 5, which is held in position by means of a securing ring 6, which is provided with two lugs 7 and 8 adapted to enter apertures 9 and 10 formed in the arms 3 and 4 of the yoke 2, when the lugs 7 and 8 55 may be riveted over so as to hold the securing ring 6 firmly in place. I preferably

provide a stop 11, adjacent the upper part of the yoke 2, as a top limit for the socket 5. A threaded cap 12 is provided to receive the stud of the junction box (not shown), or the 60 end of the loop (not shown), should the fixture be suspended from a chain.

This yoke 2 may be stamped from scrap iron, the socket may be formed of the cheapest kind of porcelain, and the securing ring 65 6 may be formed of cheap brass of very thin gauge, so that the whole makes a very inexpensive type of globe support.

In Figs. 4 and 5 I have shown a modified form of construction, in which the securing 70 ring 6 is omitted, and in its stead I provide a plurality of internal offsets 14, which are adapted to engage the bottom of the socket 5 when the arms 3 and 4 of the yoke 2 are pressed inwardly. These arms 3 and 4 are 75 held in position by means of a retaining ring 15, which is dropped over the yoke 2 and presses the arms 3 and 4 tightly against the sides of the socket 5. It may be found desirable to provide lugs 16 and 17 on the 80 inside of the retaining ring 15, to engage recesses 18 stamped in the arms 3 and 4. It will be apparent from the foregoing description that this serves to hold the socket 5 in position just as firmly as it is held by the 85 securing ring 6 in the other form of construction.

While I have shown and described specific details of construction for the device, it will be understood that these drawings are furnished for illustrative purposes only, and I do not desire to limit myself, except as may appear in the hereinafter contained claims.

Having thus described my invention, what I regard as new, and desire to secure by Letters Patent of the United States, is:

1. A globe support, comprising a porcelain socket having angular sides, a U-shaped yoke stamped to conform to said angular sides, the ends of the arms of the yoke being extended horizontally, and means to hold said socket between the arms of the yoke and in engagement with said angular configuration.

2. A globe support, comprising a porcelain socket having angular sides, a U-shaped metal yoke, the arms of which are shaped to conform to said angular sides, a securing ring mounted between the arms of the U, lugs on said ring adapted to enter apertures 100 formed in the arms of said yoke and hold the socket in place.

3. A globe-support, comprising a porcelain socket having angular sides, a U-shaped yoke, the arms of which are stamped to conform to said angular sides, stops at the top of said yoke to limit the upward movement of the socket, securing means below the socket to hold it in position, a threaded cap at the top of said yoke, the ends of the arms of the U being extended horizontally.
- 10 4. A globe support, comprising a porcelain socket having angular sides, a U-shaped yoke, the arms of which are stamped to conform to said angular sides, stops at the top of said yoke to limit the upward movement of the socket, securing means below the socket to hold it in position, a threaded cap at the top of said yoke, the ends of the arms of the U being extended horizontally, a plurality of outwardly extending shoulders on

the arms of the U above the horizontal portion. 20

5. A globe support, comprising a porcelain socket having angular sides, a U-shaped yoke, the arms of which are stamped to conform to said angular sides, the ends of the arms being extended horizontally, means to draw said arms together and hold said socket in place. 25

6. A globe support, comprising a porcelain socket having angular sides, a U-shaped yoke, the arms of the U being stamped to conform to said angular sides, the ends of said arms being extended horizontally, a plurality of shoulders on said arms adjacent their ends, and means to hold said socket between the arms of the yoke and in engagement with said angular configuration. 30 35

GEORGE AINSWORTH.
